LOCK DEVICE FOR RAILWAY TRACK
SWITCHES AND THE LIKE

Herbert L. Bone, Forest Hills, Pa., George L. Temple, Newfield, N. J., and John W. Logan, Jr., Forest Hills, Pa., assignors to The Union Switch and Signal Company, Swissvale, Pa., a corporation of Pennsylvania

Application January 9, 1947, Serial No. 721,028

21 Claims. (Cl. 246—146)

1

Our invention relates to lock devices for railway track switches, derails and like apparatus.

In railway signaling and traffic controlling systems, outlying manually operable track switches, derails, etc., are locked against operation by means of padlocks which may be opened by keys carried by certain selected railway personnel, thereby providing protection against operation of these devices by unauthorized persons. In addition, it is often necessary to supplement the padlock control by means which will permit authorized persons provided with keys for opening the padlocks, to operate a switch, derail, etc., only when conditions are proper for such operation. This supplemental control is imposed by a lock device arranged to permit movement of the switch operating lever only when the lock device is operated by either or both manual control established by a switchman in the field or an operator of a centralized traffic control system or remote control system, and automatic control established by track circuits, positions of signals, etc. A block device of this type is shown in Letters Patent of the United States No. 1,126,834, granted February 2, 1915 to W. P. Neubert et al., and a modification of this device adapted to lock the operating lever in both its normal and reverse positions is shown in Letters Patent of the United States No. 2,387,115, granted October 16, 1945 to Herbert L. Bone.

In some cases it is desirable to lock the two track switches at the opposite ends of a crossover by means of a separate stand disposed between the rails of the crossover. The center stand has a lever operatively connected with the operating mechanisms of the two track switches for locking those mechanisms against operation when the lever is in its normal or locking position, and for unlocking the two switch mechanisms to permit operation of the associated switch points when the lever is operated to its reverse or unlocking position. A switch operating mechanism adapted for control by a center stand is shown, for example, in Letters Patent of the United States No. 2,184,870, granted December 26, 1939 to Herbert L. Bone and Kenneth J. J. McGowan, and in the arrangement shown in this patent the center lock stand is arranged for padlock control only.

An object of our invention is to provide novel and improved forms of lock devices adapted for use with a center lock stand for supplementing the usual padlock control.

Another object is to provide novel and improved lock devices arranged for disposition be-

2

tween the rails of a crossover or other stretch of railway track.

Another object of our invention is to provide novel and improved lock devices incorporating means for indicating the condition of locking imposed by such devices.

Another object is to provide lock devices incorporating novel and improved means which may be utilized to shunt track circuits.

10 Another object is to provide novel and improved lock devices adapted for disposition between track rails and arranged to lock the operating lever of a stand in both its normal and reverse positions.

15 Another object is to provide lock devices incorporating novel and improved means for preventing vibrational disturbances of the operating elements which impose the locking on the operating lever governed by such devices.

20 Another object is to provide lock devices incorporating novel and improved means for preventing vibrational disturbances of the lock means when the operating lever is in its reverse position.

25 Another object of our invention is to provide novel and improved forms of lock devices of the type mentioned.

In accordance with our invention, lock devices are provided for location between the running rails of a crossover or other stretch of railway track and are arranged to provide the necessary clearances between such devices and vehicles operating on the rails. The lock devices include a locking rod biased to an intermediate position and operable between two extreme positions with locking means being provided for preventing operation of the locking rod from its intermediate position to one of the two extreme positions unless an external control is established to nullify such prevention. The operating rod is utilized

30 to control the lever latch of the lock device, to control indicating means for indicating the condition of locking imposed by such devices, and to control an interlock between the operating rod and certain functions governed thereby so as to govern an external control.

We shall describe several forms of lock devices embodying our invention, and shall then point out the novel features thereof in claims.

35 40 45 50 In the accompanying drawings, Fig. 1 is a diagrammatic view illustrating a lock device embodying our invention applied to a center stand of a crossover. Figs. 2 and 3 are top and side elevation views, respectively, showing in more detail the association of a lock device embodying

our invention to a center stand. Fig. 4 is a top view of the lock device illustrated in Fig. 2, with the cover and indication means removed in order better to illustrate the working elements of the device. Fig. 5 is a side view partially in section, of the device shown in Fig. 4. Fig. 6 is a sectional end view taken substantially on the line VI—VI of Fig. 4. Fig. 7 is a partial view showing the relationship of the contact fingers carried on insulating block 68. Fig. 8 is a view illustrating the relationship of contact fingers 14 and driving member 76. Fig. 9 is a view showing details of construction of contact operating lever 84. Fig. 10 is a view looking into window 110 of cover 23. Fig. 11 is a fragmentary view illustrating a modified form of cam 37 shown in Fig. 6. Fig. 12 is a partial view showing a modification of the device illustrated in Fig. 4. Fig. 13 is a sectional end view taken on the lines XIII—XIII of Fig. 12. Fig. 14 is a diagrammatic view showing a typical application of a lock device illustrated in Fig. 12. In each of the several views, similar reference characters refer to corresponding parts.

Referring first to Fig. 1, the reference characters W1 and W2 designate track switches located respectively at the opposite ends of a crossover connecting tracks 1 and 2. The reference characters SM1 and SM2 designate manually operable switch operating mechanisms provided for track switches W1 and W2, respectively, and each having a hand throw lever 10 operable between two extreme positions for operating the points of the associated switch between corresponding extreme positions. The mechanisms SM are of the type such as that shown in the previously mentioned Bone et al. Patent No. 2,184,870, having a locking mechanism controllable from an external point by a mechanical connection such as a pipe connection 11. The reference character CS designates a center stand having a throw lever 12 for operating the mechanical pipe connections 11. Lever 12 is operable between two extreme positions in one of which the mechanical pipe connections 11 will actuate the mechanisms SM against operation by the respective throw rods 10, and in the other extreme position of lever 12 the pipe connections 11 will be actuated to unlock the mechanisms SM to permit operation of the points of each track switch W in response to the operation of the associated throw lever 10. As is customary, the mechanisms SM incorporate circuit controllers which are controlled in part by the locking mechanisms so that certain contacts utilized in the control of external circuits governing, for example, signals controlling traffic over the switches, are operated to complete such circuits only when the mechanisms SM are locked against operation by the mechanical pipe connections 11 and the cooperating locking mechanism of the switch mechanisms SM. The control of the circuit controller of mechanisms SM in this manner by the pipe connections 11 is clearly described in the aforementioned Bone et al. Patent No. 2,184,870.

In certain applications, center stand CS is located, as shown, between the rails of the crossover substantially equidistant from the track switches W1 and W2. This center-of-track location of stand CS assists in enforcing certain predetermined sequences of operation of stand lever 12 and switch mechanism levers 10. In prior practice, as exemplified by the Bone et al. Patent No. 2,184,870, stand CS at a center-of-track location is provided only with padlock control so that operation of lever 12 is restricted to the class of

personnel provided with keys for opening the padlock. In accordance with our invention we provide a lock device WL illustrated in Fig. 1 adapted for association with lever 12 to thereby supplement the prior art padlock control of the center stand by a control which is effective to permit operation of stand CS only when conditions are proper for such operation. As previously mentioned, operation of lever 12 is permitted by the lock device WL when the latter is controlled by either or both manual control effected by a trainman in the field or an operator of a centralized traffic or remote control system, and automatic control imposed by track circuits, positions of signals, etc.

The operative association of lock device WL and stand CS is shown in more detail in Figs. 2 and 3. Referring now to Figs. 2 and 3, the stand CS comprises a base member 13 suitably fastened, as by bolts, to a support plate 14 and ties 15. Member 13 journals a shaft 16 provided on one end with a crank 17 connected by a short section of pipe 11a to a lug 18 carried on mechanical pipe connection 11 previously mentioned. The other end of shaft 16 preferably is squared to engage a correspondingly shaped opening in throw lever 12. A crank arm 19 bolted to lever 12 carries a stud 20 upon which is pivoted an adjustable lever lock rod 21 hereinafter referred to. Lever 12 of stand CS has a normal position in which it is illustrated and in which position crank 17 operates pipe 11 to cause the switch operating mechanisms SM to assume their locked positions in which operation of throw rods 10 is prevented. Lever 12 is operable through an angular movement of substantially 180° to a reverse position in which crank 17 operates pipe 11 to unlock the switch mechanisms SM to permit operation of the throw rods 10. Lever 12 as shown is locked in its normal position by lock device WL which is suitably attached, as by bolts 22a and dowels (not shown) to supporting plate 14 and the ties.

The details of construction of lock device WL embodying our invention are shown in detail in Figs. 4, 5, and 6. Referring to those figures, the lock device WL comprises a housing 22 enclosed at its upper end by a hinged cover 23 through which access to the interior of the housing may be obtained. Housing 22 is provided at its forward side with an integral extension 24 (see Fig. 6) formed at its outer end with an upturned leg 25 and with spaced vertical standards 26 which together with leg 25 form a jaw for receiving lever 12 of stand CS when and only when the lever is in the position illustrated in Figs. 2 and 3. The lower portions of standards 26 support a pivot pin 27 on which is pivotally mounted a lever latch 28 movable between a padlocked position, illustrated in Fig. 6, through an intermediate latching position to an unlatched position. In both the padlocked and intermediate positions of the lever latch, the latch projects into the upper end of the jaw in such a manner as to prevent movement of lever 12 past the latch into or out of the jaw, and in the unlatched position, latch 28 is withdrawn from the jaw to permit such movement of the lever. In the padlocked position of latch 28 a hasp lug 29 provided on leg 25 projects through opening 30 of latch 28 (see Fig. 6) and is provided with an eye 29a through which the bail of a padlock 44 may be inserted to lock latch 28 in its padlocked position. Formed integrally with latch 28 is a treadle 31 which as shown in Fig. 4 preferably bears on its upper side a legend "Lift to apply padlock," while a

bifurcated crank arm 32 also is formed integrally on latch 28 and is provided at its outer ends with slotted openings 33 which engage a pin 34 carried on the outer end of a locking rod 35 mounted for lateral sliding movement in an opening 36 in the forward side wall of housing 22.

The inner end of rod 35 which projects into housing 22 is formed of reduced diameter to provide a shoulder 42 on the rod, and the extreme inner end is threaded into a cam nut 37 slidably mounted in an opening provided in a ledge 38 formed integrally with housing 22. Sleeved collars 39 and 40 and a coil spring 41 are slipped over the reduced portion of rod 35 before attaching nut 37, with spring 41 disposed between the inner faces of the collars. When rod 35 is in its padlocked position illustrated in Fig. 6, spring 41 is provided with sufficient initial compression so that collar 39 is urged constantly by spring 41 into engagement with shoulder 42 of rod 35 while the other collar 40 is forced by spring 41 into engagement with a side of ledge 38, which constitutes a stop for collar 40. In this condition of the parts, spring 41 is compressed to bias rod 35 for movement toward the right (as viewed in Fig. 6) when the bail of padlock 44 is removed from hasp lug 29, and the parts are so proportioned that when collars 39 and 40 are in the position in which they are illustrated, and rod 35 is freed for movement by removal of the bail of the padlock from eye 28a of hasp 29, the collars 39 and 40 will be driven apart by spring 41 until collar 39 will just touch the adjacent end wall of housing 22 in which rod 35 is mounted, in which event rod 35 will be moved to the right (as viewed in Fig. 6) so as to move cam nut 37 to the position where it just touches collar 40. In this position, the collars 39 and 40 will respectively engage the confronting surfaces of shoulder 42 and cam nut 37 provided on rod 35. Nut 37 is threaded on rod 35 to a position selected so that when collars 39 and 40 are in contact with the respective confronting surfaces of shoulder 42 and nut 37, the collars 39 and 40 also respectively engage the inner face of the front wall of housing 22, and the side of ledge 38, so that the front wall and ledge respectively constitute stops for collars 39 and 40. It will be apparent, therefore, that spring 41 acts through collars 39 and 40 and the cooperating confronting surfaces on rod 35 and stops, to bias that rod to a position, hereinafter referred to as an intermediate biased position, wherein collar 39 in contact with shoulder 42 just touches the wall of housing 22 and collar 40 in contact with nut 37 just touches the side of ledge 38. In this biased intermediate position of the rod 35, the lever latch 28 is rotated in a clockwise direction (as viewed in Fig. 6) about its pivot 27 to its intermediate latching position where it projects into the jaw of the lock device so as to prevent movement of lever 12 past the latch into or out of the jaw.

The rod 35 may be moved from its intermediate biased position toward the right (as viewed in Fig. 6) to an unlatched position provided that a locking means hereinafter described is in its condition which permits this movement of the rod 35. When the rod 35 is in its unlatching position, the lever latch 28 is rotated further in a clockwise direction about pivot 27 to its corresponding unlatched position in which it is withdrawn from the jaw to permit movement of the lever 12 past the latch 28 into or out of the jaw. The locking means has a first and a sec-

ond position, in the latter of which it permits movement of the rod 35 from its biased intermediate position to its unlatched position. The locking means comprises a locking dog 45 and means, operated by either or both manual control established by a trainman in the field or an operator of a centralized traffic or remote control system, and automatic control established by track circuits, position of signals, etc., effective to operate the locking dog from its locking position to an unlocking position in which it permits movement of the rod 35 to its unlatching position.

The operating means for the locking dog 45 may, as shown in Fig. 5, be in the form in which an electromagnet operates the locking dog through the medium of a connection between the dog and the armature of the electromagnet. The locking dog 45 is carried on the end of a bar 46, the other end of which bar is secured to one arm of an angle lever 47 pivotally supported on pivot pins 48 mounted in depending lugs 49 provided on a supporting strap 50 secured by screws 51 to a magnet bracket 52 fastened by bolts 53 to housing 22. The other arm of angle lever 47 carries an armature 54 adapted to be attracted by an electromagnet 55 mounted in bracket 52. In the condition of the parts shown in the drawing, magnet 55 is deenergized and dog 45 is disposed in the path of movement of collar 40 carried on rod 35 to confine that collar between dog 45 and the side of ledge 38 and thereby prevent movement of that collar to the right (as viewed in Fig. 6). Magnet 55 when energized is effective to attract armature 54 to lift dog 45 out of the path of movement of collar 40, provided that a hold-down spring 94 and depressor 97 hereinafter referred to, are lifted clear of arm 46. Dog 45 when lifted out of the path of collar 40, permits rod 35 to be moved to the right to its unlatching position, as will be made clear hereinafter. Contacts comprising fixed and movable contact fingers (not shown in detail) mounted on a terminal block 56 secured by screws 57 to bracket 52 may be operated by armature 54 through an insulating driving member 58 connected by a pin 59 to bar 46 and suitably connected to the movable contact fingers as for example in a manner corresponding to that shown in Fig. 8 and explained hereinafter, the connection being such that an up and down movement of pin 59 effected by movement of bar 46 results in a corresponding movement of the associated movable contact fingers to suitably operate circuit controlling contacts carried by block 56. The provision of block 56 carrying contacts for operation by bar 46 is an optional feature and may be dispensed with if desired.

Housing 22 is provided with an opening 60 in its end adjacent to armature 54, and a housing member 60a is suitably secured to housing 22 in alignment with opening 60. Housing 60a contains a locking mechanism 61 which may take any desired form such as a locking mechanism of the Yale type, or as shown a mechanism operable by a switchman's key. The arrangement is such that when a proper key is inserted into the mechanism, it may be rotated in the lock chamber to rotate an actuating member 62 driven by the lock mechanism and projecting into housing 22. The actuating member 62 has a cammed surface 63 which cooperates with a mating cammed surface 64 provided on a depending spring 65 supported from supporting strip 50 and drives that spring toward armature 54 so that an insulating bead 66 carried on spring

7
65 is forced into engagement with armature 54 and drives it to the pole pieces of electromagnet 55, thereby rotating arm 46 to lift dog 45 out of engagement with collar 40. Spring 65 will be released and springs back clear of armature 54, as shown in Fig. 5, when the key is removed from the locking mechanism. As is customary, housing 60 of the lock release is preferably enclosed by a hinged cover 67 biased by a spring 67a to cover the locking mechanism of the release and suitably sealed. The provision of the locking mechanism 61 also is an optional feature and may be dispensed with, in which case opening 60 in housing 22 may be suitably enclosed by a circular blank bolted to the housing.

An insulating terminal block 68 fastened by screws 69 to the upturned leg of a contact supporting bracket 70 secured by bolts 71 to housing 22, has moulded therein two rows of contact terminal members 72 and 73 with a movable contact finger 74 riveted to each terminal 72 and a fixed contact finger 75 riveted to each terminal 73 (see Fig. 7) the fingers 74 and 75 cooperating in pairs to provide mating contacts. Each movable contact finger 74 is operatively connected with an insulated driving member 76 in any suitable manner, such as that shown in Fig. 8. Referring now to the latter figure, each movable finger 74 is provided with a longitudinal slotted opening 77 through which driving member 76 may be inserted. The member 76 is provided with slotted indentations 78 at spaced points, so that when inserted into slots 77 of fingers 74, member 76 may be rotated 90° so as to project laterally across fingers 74 with the fingers disposed in the slotted indentations of member 76. Member 76 is guided at its upper end for up and down movement in a slot guide 79 fastened by screws 80 to block 68 (see Fig. 5) and carries a laterally projecting pin 81. Block 68 and supporting bracket 70 have aligned openings 82 (see Fig. 7) through which projects an arm 83 of a pivoted operating member 84, the arm being bifurcated at its end and provided with an opening 85 in which is engaged pin 81 of driving member 76.

Operating member 84, as can best be seen in Fig. 9, is provided with integrally formed trunnions 86; with contact operating arm 83 formed on lever 84 on one side of trunnions 86; with a depending lug 87; with a cam arm 88 projecting to the other side of trunnions 86 and carrying at its outer end a cam follower 89 secured to the arm as by studs 90; and with another arm 91 also projecting to the other side of trunnions 86 and to which is secured by tap bolts 92 a depressor bracket 93. A depressor spring 94 disposed for axial alignment with bracket 93, and a laterally projecting member 95, are attached to the outer end of bracket 93 by means of screws 96 passing through bracket 93 and threaded into suitable openings provided in a depressor 97 disposed in axial alignment with bracket 93.

Operating member 84 as shown in Fig. 4 is pivotally supported by its trunnions 86 which are journaled respectively in a bushing 98 provided in an opening 99 formed in a boss 100 on the rear sidewall of housing 22, and in a trunnion screw 101 threaded through an opening 102 in the forward sidewall of housing 22 and secured by a nut 105. Lug 87 on operating member 84 cooperates with a coil spring 103 confined between the lug and a boss 104 formed on housing 22 to bias member 84 in a clockwise direction.

5 (as viewed in Fig. 5) about its points of pivotal support, and in this biased clockwise position of member 84, cam follower 89 on cam arm 88 is disposed in engagement with cam nut 37 on rod 35 (see Fig. 6), with the beveled cam surface of follower 89 disposed just clear of a mating beveled surface of nut 37 while depressor spring 94 carried by arm 91 is forced firmly into engagement with the top of lever 46 (see Fig. 5) carrying dog 45. Depressor 97 is disposed above and just clear of lever 46 and the parts are so proportioned that spring 94 holds down lever 46 with sufficient force to overcome any tendency of the lever to raise dog 45 out of engagement with collar 40, as for example due to energization of magnet 55, or in response to vibrational disturbances of the mechanism such as would be occasioned by passing trains, etc. Pin 81 of driving member 76 is positioned by arm 83 of member 84 so that the contacts carried by block 68 assume the positions in which they are shown in Fig. 7.

20 The lock device WL also includes indicator means for indicating the condition of locking imposed by the device. The indicator means is capable of displaying one or another of a plurality of legends visible through a window 110 in an opening 111 provided in the forward edge of cover 23 (see Figs. 5 and 6) and preferably the 25 legends are of the type shown in Fig. 10. Located behind the window and suitably supported from housing 22 is a shield 112 with a slot 113 which limits the display of the legend to that proper under the particular circumstances. The legends 30 are carried on an arcuate member 114 carried by a rod 115 forming a part of or rigidly secured to a member 116 pivotally supported on a pin 117 journaled in the sidewalls of a U-shaped member 118 secured by screws 119 to a plate 120 35 fastened by bolts 121 to a projecting boss on the forward sidewall of housing 22. Member 116 is provided with a boss 122 engageable by member 95 secured to depressor bracket 93 (see Fig. 9). Member 116 also is provided with a weight arm 124 which projects on the opposite side of pin 40 117 from rod 115 to bias that rod and arcuate member 114 in a counterclockwise direction as viewed in Fig. 6, and weight arm 124 carries a depending adjustable screw 125 which projects 45 through an aligned opening 126 in the depressor bracket 93 and the associated depressor spring 94 and depressor 97. The depending screw 125 is arranged to be disposed in the path that dog 45 travels when armature 54 is attracted by electromagnet 55. The parts are so proportioned 50 that in the condition illustrated in Fig. 6, that is with depressor bracket 93 rotated to its biased clockwise position as illustrated in Fig. 5, member 95 carried by bracket 93 engages boss 122 to cause arcuate member 114 to be rotated to one 55 extreme position in which the legend "Padlocked" is positioned immediately below slot 113 in shield 112 so as to be visible through window 110. When arm 95 carried by bracket 93 is lifted 60 away from the position shown in Fig. 6 in a manner to be made clear hereinafter, weight arm 124 causes member 116 to rotate in a counterclockwise direction as viewed in Fig. 6 so that arcuate member 114 is rotated to another extreme position 65 in which the legend "Locked" is disposed beneath slot 113 to be visible through window 110. With the parts of Fig. 6 in the condition just explained, depending screw 125 carried by weight arm 124 is moved to a position in which it just 70 clears dog 45, and the screw is adjusted so that 75

when dog 45 is actuated out of the path of collar 40 by the energization of magnet 55, the dog will engage screw 125 to rotate member 116 in a clockwise direction to an intermediate position in which which the legend "Unlocked" is positioned beneath slot 113 for view through window 110. Preferably, as shown, the shield 112 functions as a stop for arcuate member 114 in each of its two extreme positions and therefore acts to assist in determining such extreme positions of member 114.

The operation of the apparatus as a whole is as follows: When lever 12 of center stand CS is locked by device WL in the manner indicated in Figs. 2 and 3, the parts of the lock device will occupy the positions in which they are shown in Figs. 4, 5, and 6. That is to say, the bail of padlock 44 is inserted into eye 23a of hasp 29 formed on leg 25 to lock lever latch 28 in its padlocked position in opposition to the bias of spring 41, dog 45 is disposed in the path of travel of collar 40 carried by rod 35, and member 84 is rotated to its extreme clockwise position by the bias of spring 103 so that depressor spring 94 rides on arm 46, depressor 97 is located above arm 46 and just clears that arm, and member 95 engages boss 122 of member 116 to rotate arcuate member 114 to its one extreme position in which the legend "Padlocked" is visible through window 113.

When it is desired to reverse lever 12, treadle 31 is first lifted upwardly in order to release the force of latch 28 on the bail of the padlock, and the bail is then removed from eye 23a and treadle 31 released. This permits spring 41 to move rod 35 to the right (as viewed in Fig. 6) until the rod reaches its previously mentioned intermediate position wherein cam nut 37 engages the outer face of collar 40 and collar 39 in contact with shoulder 42 just touches the inner wall of housing 22. Further movement of rod 35 at this time will be limited by locking dog 45 engaging the inner face of collar 40 to prevent movement of that collar and correspondingly prevent movement of cam nut 37 attached to rod 35. The restricted movement of rod 35 toward the right at this time results in a corresponding movement of pin 34 at the outer end of the rod to rotate latch 28 about pivot pin 27 so that the latch is withdrawn slightly from the jaw and treadle 31 is lowered slightly, but in this particular position of the parts the latch 28 is still positioned so as to be effective to prevent movement of lever 12 into or out of the jaw of the locked device. Latch 28 will now occupy the previously mentioned intermediate latching position corresponding to the intermediate position of rod 35. In this condition of rod 35, cam nut 37 lifts cam follower 89 to rotate member 94 counterclockwise (as viewed in Fig. 5) in opposition to the bias of spring 103. Depressor spring 94 is lifted out of engagement with arm 46 carrying locking dog 45 while depressor 97 likewise is lifted out of its previous position closely adjacent to arm 46. Member 95 carried by depressor bracket 93 also is lifted away from boss 122 of member 116 and permits that member to rotate under the influence of weight arm 124 so as to rotate arcuate member 114 to its other extreme position in which the legend "Locked" is visible through window 110. The pin 34 carried in opening 65 on the extreme end of arm 83 of member 84 is moved downwardly as viewed in Fig. 5 and operates driving member 76 in the same direction to operate the movable contact fingers 78 to open normally closed or close normally open contacts, as the case may

be, carried by terminal board 68. One or more of the contacts of terminal board 68 may be used in the external control circuit by which it is intended that electromagnet 55 will be energized, and it is contemplated that such a control circuit may take any one of a number of forms well known to the art, such as the control circuit shown in Fig. 4 of Neubert et al. Patent No. 1,126,834, or the circuits shown in Letters Patent of the United States No. 2,367,723 granted on January 23, 1945 to H. A. Haines. In such a circuit arrangement, a contact completed by movable finger 74 in engagement with fixed finger 75 will of course correspond to the lock operated contacts 46a-47 of the Neubert et al. patent and 46-47 of the Haines patent. It follows that when a contact 74-75 is established by movement of driving member 76 in the manner explained, and if conditions are proper for movement of lever 12 to its unlocking position to permit operation of switches W by their associated switch operating mechanisms SM, that is, if the external control circuit for magnet 55 is completed either manually by the operator of a control system, or automatically by devices such as track relays, signal control relays, etc., then magnet 55 will be energized. Assuming that magnet 55 is energized, locking dog 45 will be operated out of the path of movement of collar 40 carried on rod 35, and will actuate driving member 53 to operate the contacts carried by terminal block 56, which contacts may be used for any suitable purpose. Dog 45 will also engage screw 125 carried by arm 124 of member 116 to rotate that member to the previously mentioned intermediate position in which the legend "Unlocked" is positioned beneath slot 113 of shield 112 to be visible through window 110. The display of this legend indicates that lock device WL is now in the condition for further operation to unlatch lever 12. Treadle 31 may now be depressed to rotate latch 28 about pin 27. Rotation of latch 28 results in movement to the right, as viewed in Fig. 6, of pin 34 carried on the outer end of rod 35 and causes cam nut 37 to drive collar 40 to the right and compress spring 41, the other collar 39 in this case being restricted in movement by engaging the inner face of the front sidewall of housing 22. The depression of treadle 31 results in the movement of latch 28 out of the jaw of the lock device and beyond the path of movement of lever 12 so as to free that lever for operation through an angle of approximately 180° to its reverse position previously mentioned.

Movement of lever 12 to its reverse position operates pipe 11 through pipe connection 11a secured to crank 17 of center stand CS and as previously mentioned when lever 12 reaches its full reverse position the pipes 11 will actuate the locking mechanisms of switch mechanisms SM to permit operation of switches W by their associated throw levers 18. During the initial portion of the movement of lever 12 to its reverse position lever lock rod 21 will be actuated by crank 19 carried on lever 12 and will move behind a lug 43 formed on latch 28 to prevent return of latch 28 to its biased intermediate position under the influence of spring 41 which is now compressed between the collars 39 and 40 and operates to bias rod 35 toward its previously mentioned intermediate position. The lever lock rod 21 is adjustable and is arranged to engage lug 43 of latch 28 before the bottom of lever 12 is operated clear of latch 28.

If desired, the lock device WL embodying our invention may be provided with a tandem lock

arrangement shown and claimed in previously mentioned Bone Patent No. 2,387,115, in which case lever 12 may be locked in its reverse position through the medium of lock device WL, as well as through the usual padlock control customarily employed.

Assuming that lock device WL is arranged as shown to lock lever 12 only in its normal position, the lever may be restored to its normal position and when it enters the jaw of lock device WL, lever lock rod 21 is withdrawn from engagement with lug 43 of latch 28, so that latch 28 is free to be operated to its intermediate latching position as soon as lever 12 is restored to its full normal position, in which event rod 35 will be operated by spring 41 to its biased intermediate position to rotate latch 28 about pin 27 to its corresponding intermediate position. As is customary in switch lock control circuits, the circuit for magnet 55 ordinarily will have been opened before lever 12 is restored to its normal position, consequently when rod 35 reaches its biased intermediate position, collar 40 will be in its normal position as shown in Fig. 6, dog 45 will drop beside the inner face of collar 40, and member 116 will again rotate to its other extreme position wherein the legend "Locked" will be displayed through window 110. Treadle 31 may now be grasped and lifted upwardly to swing latch 28 to the position illustrated in Fig. 6 wherein the bail of a padlock may be inserted in eye 28a of hasp 29, thereby restoring these parts to the normal padlock condition. Operation of latch 28 to its padlocked position results in driving rod 35 toward the left to the position illustrated in Fig. 6, to compress spring 41 between collars 39 and 40 and to move cam 37 out of engagement with the cammed surface of follower 89, thereby allowing cam arm 88 to drop and permit member 84 to rotate under the bias of spring 103, to the position illustrated in Fig. 5. In such position of member 84, contacts operated by driving member 76 will assume the normal positions shown in Fig. 7, while member 95 carried by member 84 will engage boss 122 on rotatable member 116 to cause rotation of arcuate member 114 so that the legend "Padlocked" is displayed through window 110. All of the parts of the switch lock device embodying our invention will therefore be restored to the normal condition illustrated in the drawings.

An inter-lock between pivoted operating member 84 and armature 54 of electromagnet 55 will be established through spring 94 carried on arm 91 of member 84, so that if magnet 55 remains energized when treadle 31 is lifted to restore latch 28 to its padlocked position, spring 94 will engage arm 46 and drive dog 45 down beside collar 40 of rod 35, thereby providing a forced drop feature for the locking dog to assure that dog 45 is in its locking position when latch 28 is moved to its padlocked position. The depressor 97 will function to assist spring 94 in this hold-down action if the spring should weaken, and will function in place of spring 94 if the spring should break. The depressor 97 also cooperates with spring 94 in the event that the parts of the lock should become deranged or out of adjustment so that if, when latch 28 is restored to its padlocked position, dog 45 does not clear collar 40 so as to be able to drop beside that collar, then arm 46 will engage both spring 94 and depressor 97 to prevent rotation of member 84 to its normal position when cam 37 disengages from follower 89, and as a result the contacts operated by arm 83 of the lever

will remain in their operated position and will not be restored to their normal positions, illustrated in Fig. 7, while dog 45 will permit weight arm 124 to rotate arcuate member 114 slightly so that a part of both legends "Unlocked" and "Padlocked" will appear through window 110. This display with latch 28 restored to its padlocked position will indicate that the parts of the lock device have not restored to normal, and will call attention to the fact that correction of a fault in the lock device is required.

The lock device shown in Fig. 6 may be modified as illustrated in Fig. 11 to provide a hold-down feature for locking dog 45 when the treadle 15 31 is depressed to its unlocking position. This feature is desirable in those applications where the lock device is required to lock the hand throw 20 lever 12 in its reverse position only. In such an arrangement the lever in its normal position actuates lever lock rod 21 to hold treadle 31 in its 25 depressed position against the restoring bias of spring 41 of rod 35, and since in this arrangement the hand throw lever is in its locked reverse position for only relatively short intervals of 30 time, the lock device normally stands in a position wherein the dog 45 is subjected to vibrational disturbances and unless the dog is restrained from vibrating or rattling, the pivot pins 48 supporting 35 armature 54 may be subject to excessive wear. 30 This wear of the pivot pins 48 may be avoided in such applications by substituting for cam nut 37 of Fig. 6 a cam nut 37a as shown in Fig. 11 provided with a cam surface arranged to permit cam arm 88 and follower 89 to drop slightly when rod 35 operates to its extreme right-hand position, as viewed in Fig. 6, so that depressor spring 94 rides on arm 46 to hold down arm 46 against vibrational movement. In this condition of the parts, the collar 40 is moved to the right to a position 40 underneath dog 45 so that only a slight movement downwardly of spring 94 is necessary in order for the spring to force dog 45 into engagement with the top of collar 40. The contacts operated by 45 driving member 76 are preferably provided with a small amount of overtravel so that the slight downward movement of cam arm 94 permitted by cam 37a in the unlocked position of treadle 31 is not sufficient to alter the operation of the contacts operated by contact arm 83 of member 84 through driving member 76, hence the cam 37a of Fig. 11 permits dog 45 to be held down by 50 depressor spring 94 in the unlocked position of the latch, while allowing the lever operated contacts carried by terminal board 68 to remain in the positions assumed by such contacts when member 84 is rotated by movement of rod 35 to its biased intermediate position following removal of the bail of the padlock from hasp 29.

The lock devices embodying our invention are 60 arranged for emergency release operation effected through the medium of locking mechanism 61 provided for housing 60a attached to the switch lock casing adjacent to electromagnet 55. The emergency release feature may be used in case the 65 external control circuit for magnet 55 does not become completed to energize that magnet after rod 35 assumes its biased intermediate position following removal of the padlock from hasp 29. If with rod 35 and latch 28 in corresponding 70 intermediate positions, it is desired to obtain an unlock of lever 12 and energization of magnet 55 can not be effected through its external circuit, then emergency operation of the lock device may be obtained by breaking the seal so that the cover 75 61 may be opened to insert a proper key in mecha-

nism 61. Rotation of the key permitted by the tumblers of mechanism 61 results in operation of actuating member 62 to actuate cam 64 carried on spring 65, with the result that bead 66 on spring 65 is forced into engagement with armature 54 and drives that armature into the pole pieces of electromagnet 55, thereby lifting arm 46 and operating dog 45 out of the path of collar 40. This action permits treadle 31 to be depressed to release lever 42. When actuating member 62 is restored to its normal position as illustrated in Fig. 5 by rotation of the key preliminary to removing the key from mechanism 61, cam 64 will permit spring 65 to operate bead 66 out of engagement with armature 54, and the parts of the emergency release will assume the normal condition illustrated in Fig. 5.

The contact structure previously described in connection with Figs. 5, 7, and 8 may be modified in accordance with our invention as shown in Figs. 12 and 13 to provide a structure which may be used to apply a shunt across the track rails of the associated tracks, as indicated diagrammatically in Fig. 14. In connection with the modified form of our invention shown in Figs. 12 and 13, it is contemplated that the contact structure illustrated in these figures will be substituted for the contact structure shown in Figs. 4 and 5, that housing 22 previously described will be modified slightly as shown in Fig. 13 to provide external contact lugs, that contact operating lever 84 previously described and shown in Fig. 9 will be modified slightly in a manner explained hereinafter, but that all other parts of the lock device will be the same as previously described.

Referring now to Figs. 12 and 13, the contact structure there shown comprises an upright insulating terminal board 130 secured by bolts 131 to housing 22. Board 130 is disposed longitudinally in the housing and each face of the board is provided with contact terminals 133 to which cooperating fixed and movable contact fingers 134 and 135, respectively, are riveted. As shown in Fig. 12, three such pairs of cooperating fixed and movable contact fingers are provided on the forward face of board 130, while a similar number of pairs of contact fingers may be provided on the rear face of the board, as indicated in Fig. 13. Contact driving members 136 are provided for each face of board 130 and are guided at the top for up and down movement in a slotted guide 137 disposed between the top of board 130 and bolts 131. Each driving member 136 comprises two insulating strips 138 spaced apart by an insulating block 139 and sleeves 140. The block 139 is secured to the top of members 138 by rivets 141, while sleeves 140 are carried on rivets 142 located at spaced points along members 138. The sleeves 140 may be located in pairs one on either side of a contact finger 135 so as to obtain a positive drive of that finger in both the up and down direction, or singly to provide a drive in only one direction. The sleeves 140 provide a driving connection between member 136 and the movable contact fingers 135 which are inserted between the two spaced strips 138 adjacent to the sleeves 140, as is readily apparent from an inspection of Fig. 13. Preferably, the movable fingers 135 are biased into engagement with the mating fixed fingers 134 so as to close with an appreciable contact pressure.

Board 130 is slotted at its lower end to permit up and down movement of a driving pin 143 carried at the lower end of both driving members 136

136. The pin 143 is operated by arms 83a of pivoted operating member 84, the member 84 in the case of the apparatus of Figs. 12 and 13 being slightly modified to provide two contact operating arms, one disposed on either side of lug 87, in place of the one contact arm 83 illustrated in Fig. 9. The arms 83a of operating member 84 of Fig. 13 are slotted to receive pin 143 and both arms 83a operate in unison to drive contact operating members 136 up or down, as the case may be, to effect a corresponding movement of the associated movable contact fingers 135.

As shown in Fig. 13, the rear sidewall of housing 22 is formed with an opening 144 through which a plurality of terminal lugs 145 may be inserted into the interior of the housing, the opening being disposed longitudinally in the rear sidewall of housing 22 to accommodate the plurality of lugs 145. The lugs 145 are separated from each other by insulating material, and are sandwiched between insulating strips 146 which are inserted between lugs 145 and the lips of opening 144. Bolts 147 passing through the upper lip of opening 144 and the insulating material, avoiding lugs 145, are threaded into a plate 149 to clamp the terminal lugs and insulation tightly together to provide a weatherproof seal. The inner ends of lugs 145 which project within housing 22 carry terminal screws 148 which enable circuit wires to be connected to the lugs 145, and it is contemplated that the other ends of these circuit wires will be connected to the contact terminals 133 carried by board 130.

As illustrated in Fig. 12, the contact fingers 135 are normally positioned against their bias away from their mating fixed fingers 134 when the lock device is in its normal padlocked position. Operating member 84 will operate to drive the fingers 135 of Fig. 12 downwardly, as viewed in that figure, into engagement with the mating fixed fingers 134 when the lock device operates to its biased intermediate position, in a manner corresponding to that hereinbefore described in detail in connection with the description of the operation of the device shown in Figs. 4, 5, and 6. The operation of the contact structure will be apparent from an inspection of Figs. 12 and 13 and the foregoing description of the operation of the lock device as a whole, and further detailed explanation is unnecessary, except that it should be noted that the bias of contact fingers 135 is in opposition to the bias of operating member 84 and therefore may assist operation of member 84 to its counterclockwise direction. Also, where a movable finger 135 is engaged by a pair of sleeves 140, the upper sleeve will drive that finger firmly into engagement with the mating fixed finger 134, thereby assuring establishment of an intimate electrical contact between such fingers.

In view of the positive mechanical drive of fingers 135 into engagement with fingers 134, the resulting contact may be utilized to establish a shunt path across the two track rails of a stretch, through which shunt path the track circuit current in the rails may be diverted from the track relay customarily employed in railway signaling practice. This shunt path established by contacts of a lock device embodying our invention may be used in the control of signals, etc., governed by such track circuits, as will be readily obvious from an inspection of Fig. 14.

Referring now to Fig. 14, the contacts 134 and 135 diagrammatically represented in this figure correspond to the similarly numbered contacts

shown in Fig. 12. As will be apparent from Fig. 14, contact fingers 135 occupy their normal positions out of engagement with fingers 134 when the lock device WL is in its padlocked condition, and fingers 135 are operated into engagement with fingers 134 when lock device WL is in either its locked or unlocked condition previously described. A pair of fingers 134 are electrically connected to one rail of a stretch of track, while a mating pair of fingers 135 are electrically connected to the other rail, consequently when the fingers 134 and 135 are in engagement a low resistance path is established between the track rails, through which path may flow the track circuit current which it is contemplated will be supplied to the track rails in series. If desired, some of the contacts on board 130 of Fig. 12 may be used for line circuit control, as is obvious from an inspection of Fig. 14. For such line circuit control, positive drive of finger 135 to engage its mating fixed finger 134 may not be necessary, consequently such a contact can be operated by means of only a single sleeve 140 on member 138, the arrangement being similar to that shown for the upper contact finger 135 illustrated in Fig. 12. As indicated in Fig. 14, the line circuit may be utilized in the control of the electromagnets 55 of the lock device, corresponding to the previously mentioned control of the electromagnets by the contacts of the lock device shown in Figs. 4, 5 and 6.

It is to be understood that while we have illustrated and described lock devices embodying our invention in connection with a center stand provided for a crossover, the lock devices are equally applicable to the control of the throw lever of a switch operating mechanism, such as lever 10 of switch mechanism SM1 or SM2 illustrated in Fig. 1. The application of our lock device to a switch mechanism will be obvious. Similarly, our lock device may be applied to the throw lever of a derail, etc. In applications to the throw rod of a switch mechanism or derail, our lock device may be mounted outside of the running rails of the track in accordance with the customary practice.

Important advantages of lock devices embodying our invention reside in the provision of means for indicating the three conditions of locking provided by the devices, and in the provision of contacts operated by the locking mechanism for controlling either or both line and track circuits. Other advantages reside in the arrangement to provide a positive interlock between the circuit controlling contacts and the locking dog, and in the arrangement of the parts which permit application of the holdown spring to the locking dog when the latch is moved to its unlocking position. Another advantage results from the fact that our lock devices are readily adaptable for use with the tandem lock arrangement to lock a throw lever in its reverse position as well as the normal position, while an important advantage of the lock devices embodying our invention results from the ability to locate the lock devices between the running rails of a track so that electrical locking may be imposed on throw rods located between such track rails.

Although we have herein shown and described only a few forms of lock devices embodying our invention, it is to be understood that various changes and modifications may be made therein within the scope of the appended claims without departing from the spirit and scope of our invention.

Having thus described our invention, what we claim is:

1. In combination with a throw lever operable between two extreme positions and disposed between the rails of a track over which railway vehicles operate, a lock device disposed between the track rails and having a jaw for receiving the throw lever in one of its said two extreme positions, said lock device providing adequate clearance between its parts and vehicles operating over said track, a latch for said lock device operable between a first and a second position, said latch in its said first position projecting into said jaw for preventing movement of said throw lever past said latch, said latch in said second position being withdrawn from said jaw, and controllable means operatively connected with said latch for preventing movement of said latch from its said first to its said second position unless said means is operated.

2. In combination with a crossover provided with manually operable switch throwing mechanisms for operating the track switches at the opposite ends thereof, and having disposed between the rails of said crossover a center stand including a throw lever operatively connected with said switch throwing mechanisms and operable between two extreme positions in one of which said throw lever locks said mechanisms against operation, a lock device disposed between the track rails and having a jaw for receiving the throw lever in one of its said two extreme positions, said lock device providing adequate clearance between its parts and vehicles operating over said crossover, a latch for said lock device operable between a first and a second position, said latch in its said first position projecting into said jaw for preventing movement of said throw lever past said latch, said latch in said second position being withdrawn from said jaw, and controllable means operatively connected with said latch for preventing movement of said latch from its said first to its said second position unless said means is operated.

3. In combination with the throw lever of a center stand disposed between the rails of a crossover and operatively connected with switch throwing mechanisms at the opposite ends of said crossover for respectively locking and unlocking said mechanisms according as said throw lever is in one or another of two extreme positions, a lock device disposed between the rails of said crossover; said lock device providing for adequate clearance between its parts and vehicles operating over said crossover and comprising a jaw for receiving said throw lever in one of its said two positions, a latch movable between a first position and a second position, said latch in said first position projecting into said jaw for preventing movement of the throw lever past said latch, said latch in its said second position being withdrawn from said jaw, locking means having a first and a second condition in the latter of which movement of said latch from its said first to its said second position is arrested at an intermediate position, and means controlled in part by said latch in said intermediate position for operating said locking means to its said first condition for freely permitting movement of said latch past said intermediate position to its said second position.

4. In combination with the throw lever of a center stand disposed between the rails of a crossover and operatively connected with switch throwing mechanisms at the opposite ends of said

crossover for respectively locking and unlocking said mechanisms according as said throw lever is in one or another of two extreme positions, a lock device disposed between the rails of said crossover; said lock device providing for adequate clearance between its parts and vehicles operating over said crossover and comprising a jaw for receiving said throw lever in one of its said two positions, a latch movable between a first position and a second position, said latch in said first position projecting into said jaw for preventing movement of the throw lever past said latch, said latch in its said second position being withdrawn from said jaw, locking means having a first and a second condition in the latter of which movement of said latch from its said first to its said second position is arrested at an intermediate position, means controlled in part by said latch in said intermediate position for operating said locking means to its said first condition for freely permitting movement of said latch past said intermediate position to its said second position, means for biasing said latch to its said intermediate position, and means operatively connected with said throw lever for retaining said latch in its said second position when said throw lever is out of said jaw.

5. In combination with the throw lever of a center stand disposed between the rails of a crossover and operatively connected with switch throwing mechanisms at the opposite ends of said crossover for respectively locking and unlocking said mechanisms according as said throw lever is in one or another of two extreme positions, a lock device disposed between the rails of said crossover; said lock device providing for adequate clearance between its parts and vehicles operating over said crossover and comprising a jaw for receiving said throw lever in one of its said two positions, a latch movable between an intermediate and two extreme positions, said latch in said intermediate and one extreme position projecting into said jaw for preventing movement of the throw lever past said latch, and said latch in the other of its said extreme positions being withdrawn from said jaw, locking means having a first and a second condition in the latter preventing movement of said latch from said intermediate position to said other extreme position while freely permitting movement of said latch between said intermediate position and said one extreme position, means for locking said latch in said one extreme position, and means operatively connecting said latch with said locking means for restricting said locking means to its said second condition when said latch occupies its said other extreme position and effective in said intermediate position of said latch to permit operation of said locking means to its said first condition.

6. In combination with the throw lever of a center stand disposed between the rails of a crossover and operatively connected with switch throwing mechanisms at the opposite ends of said crossover for respectively locking and unlocking said mechanisms according as said throw lever is in one or another of two extreme positions, a lock device disposed between the rails of said crossover; said lock device providing for adequate clearance between its parts and vehicles operating over said crossover and comprising a jaw for receiving said throw lever in one of its said two positions, a latch movable between an intermediate and two extreme positions, said latch in said intermediate and one extreme position projecting

into said jaw for preventing movement of the throw lever past said latch, and said latch in the other of its said extreme positions being withdrawn from said jaw, means operatively connected with said latch for biasing said latch to its said intermediate position, locking means having a first and a second condition for respectively permitting and preventing movement of said latch from said intermediate position to said other extreme position, means operatively connected with said latch for controlling said locking means to its said first or said second position according as said latch occupies its said one extreme position or its said intermediate position, and means operatively connected with the throw lever for retaining said latch in its said other extreme position when said throw lever is out of said jaw.

7. In a lock device having a latch and a slidably mounted rod operatively connected with said latch for movement between an intermediate and two extreme positions; means for biasing said sliding rod to its said intermediate position comprising two collars slidably mounted on said rod, a shoulder on said rod and a stop for one of said collars, a member secured to said rod and a stop for the other of said collars, a spring disposed between said collars for biasing said collars against the respective shoulder and member, said stops being disposed to engage the respective collars when said collars are in biased engagement with said shoulder and member; a dog disposed in engagement with said other collar for confining it into engagement with its stop while freely permitting movement of said rod from said intermediate position to one extreme position wherein said shoulder drives said one collar away from its stop against the bias of said spring and said member moves away from said other collar, means for locking said rod in its said one extreme position, and means controlled in part by said member when in engagement with said other collar for operating said dog out of engagement with said other collar, thereby to permit movement of said rod from said intermediate position to the other of said extreme positions wherein said member drives said other collar away from its stop against the bias of said spring with said shoulder moving away from said one collar engaged by its stop.

50 8. In a lock device having a latch and a slid-
ably mounted rod operatively connected with said
latch for movement between an intermediate
and two extreme positions; means for biasing
said sliding rod to its said intermediate position
comprising two collars slidably mounted on said
rod, a shoulder on said rod and a stop for one
of said collars, a member secured to said rod
and a stop for the other of said collars, a spring
disposed between said collars for biasing said
collars against the respective shoulder and mem-
ber, said stops being disposed to engage the re-
spective collars when said collars are in biased
engagement with said shoulder and member; a
60 dog disposed in engagement with said other col-
lar for confining it into engagement with its stop
while freely permitting movement of said rod
from said intermediate position to one extreme
position, means for locking said rod in its said
one extreme position, means controlled in part
65 by said member when in engagement with said
other collar for operating said dog out of en-
gagement with said other collar, thereby to
permit movement of said rod from said interme-
diate position to the other of said extreme posi-
70 tions, and means controlled jointly by said slid-
75 ing rod and said member for controlling the
engagement of said dog with said other collar.

ing rod and by said dog for indicating the condition of locking imposed by said lock device.

9. In a lock device having a jaw for receiving a hand throw lever, a rod slidably mounted for movement between an intermediate and two extreme positions, a latch operatively connected with said slidably mounted rod and operable between corresponding intermediate and extreme positions, said latch in said intermediate and one extreme position projecting into said jaw for preventing movement of a throw lever past said latch, said latch in the other of its said extreme positions being withdrawn from said jaw; means for biasing said slidably mounted rod to its said intermediate position comprising two collars slidably mounted on said rod, a shoulder on said rod and a stop for one of said collars, a member secured to said rod and a stop for the other of said collars, a spring disposed between said collars for biasing said collars against the respective shoulder and member, said stops being disposed to engage the respective collars when said collars are in biased engagement with said shoulder and member; a dog disposed in engagement with said other collar for confining it into engagement with its stop while freely permitting movement of said rod from said intermediate position to one extreme position, means for locking said rod in its said one extreme position, and means controlled in part by said member when in engagement with said other collar for operating said dog out of engagement with said other collar, thereby to permit movement of said rod from said intermediate position to the other of said extreme positions.

10. In a lock device, an operating member slidably mounted for movement between an intermediate and two extreme positions, means for biasing said operating member to its said intermediate position comprising two confronting surfaces provided on said member at spaced points, two sleeve collars slidably mounted on said member and a spring confined between said collars for biasing the collars respectively into engagement with said surfaces, stops disposed to engage said collars when in biased engagement with said surfaces, a locking member disposed to engage one of said collars for confining it against its stop, thereby freely permitting movement of said member from said intermediate to one of said extreme positions while preventing movement of said member from said intermediate to the other of said extreme positions, means for operating said locking member out of confining engagement with its said one collar, means operatively connected with said operating member preventing operation of said locking member in said one extreme position of said locking member, and a manually operable latch operatively connected with said operating member for movement between corresponding intermediate and extreme positions, said latch in said intermediate and the corresponding one extreme position projecting into the jaw of said lock device for preventing movement of a throw lever past said latch, and said latch in the corresponding other extreme position being withdrawn from said jaw.

11. In a lock device, an operating member slidably mounted for movement between an intermediate and two extreme positions, means for biasing said operating member to its said intermediate position comprising two confronting surfaces provided on said member at spaced points, two sleeve collars slidably mounted on

said member and a spring confined between said collars for biasing the collars respectively into engagement with said surfaces, stops disposed to engage said collars when in biased engagement with said surfaces, a locking member disposed to engage one of said collars for confining it against its stop, thereby freely permitting movement of said member from said intermediate to one of said extreme positions while preventing movement of said member from said intermediate to the other of said extreme positions, means for operating said locking member out of confining engagement with its said one collar, means operatively connected with said operating member preventing operation of said locking member in said one extreme position of said operating member, and a manually operable latch operatively connected with said operating member for movement between corresponding intermediate and extreme positions, said latch in said intermediate and the corresponding one extreme position projecting into the jaw of said lock device for preventing movement of a throw lever past said latch, and said latch in the corresponding other extreme position being withdrawn from said jaw.

12. In a lock device, an operating member mounted for movement between an intermediate and two extreme positions, means for biasing said operating member to its said intermediate position comprising two confronting surfaces provided on said member at spaced points, two sleeve collars slidably mounted on said member and a spring confined between said collars for biasing the collars respectively into engagement with said surfaces, stops disposed to engage said collars when in biased engagement with said surfaces, a locking member disposed to engage one of said collars for confining it against its stop, thereby freely permitting movement of said member from said intermediate to one of said extreme positions while preventing movement of said member from said intermediate to the other of said extreme positions, means for operating said locking member out of confining engagement with said one collar, means operatively connected with said operating member for confining said locking member in engagement with its said collar in said one extreme position of said operating member, an indicator means, means for controlling said indicator means by said operating member for causing said indicator means to display a first or a second indication according as said operating member occupies its said one extreme position or its said intermediate position, means for controlling said indicator means by said locking member for causing said indicator means to display its said second indication or a third indication according as said locking member is or is not in confining engagement with said one collar, and a manually operable latch operatively connected with said operating member for movement between corresponding intermediate and extreme positions, said latch in said intermediate and the corresponding one extreme position projecting into the jaw of said lock device for preventing movement of a throw lever past said latch, and said latch in the corresponding other extreme position being withdrawn from said jaw.

13. In a lock device, an operating member

75 slidably mounted for movement between an

intermediate and two extreme positions, means for biasing said operating member to its said intermediate position comprising two confronting surfaces provided on said member at spaced points, two sleeve collars slidably mounted on said member and a spring confined between said collars for biasing the collars respectively into engagement with said surfaces, stops disposed to engage said collars when in biased engagement with said surfaces, a locking member disposed to engage one of said collars for confining it against its stop, thereby freely permitting movement of said member from said intermediate to one of said extreme positions while preventing movement of said member from said intermediate to the other of said extreme positions, means for operating said locking member out of confining engagement with said one collar, contacts operable between a first and a second position, means operatively connecting said contacts with said operating member for operating said contacts respectively to said first or said second position according as said operating member occupies its said one extreme position or said intermediate position, means interlocking said contacts with said locking member for arresting said contacts in said second position if said locking member is out of engagement with said one collar when said operating member assumes its said one extreme position, and a manually operable latch operatively connected with said operating member for movement between corresponding intermediate and extreme positions, said latch in said intermediate and the corresponding one extreme position projecting into the jaw of said lock device for preventing movement of a throw lever past said latch, and said latch in the corresponding other extreme position being withdrawn from said jaw.

14. In a lock device, an operating member slidably mounted for movement between an intermediate and two extreme positions, means for biasing said operating member to its said intermediate position comprising two confronting surfaces provided on said member at spaced points, two sleeve collars slidably mounted on said member and a spring confined between said collars for biasing the collars respectively into engagement with said surfaces, stops disposed to engage said collars when in biased engagement with said surfaces, a pivotally supported locking member rotatable between two positions in one of which said locking member is disposed in engagement with one of said collars for confining that collar into engagement with its said stop, means for rotating said locking member about its pivots to the other of said two positions wherein said locking member disengages from said one collar, a pivoted member provided with a depressor spring for holding down said locking member against vibrational disturbances, means for biasing said pivoted member to a first position wherein said depressor spring rides on said locking member in its said one position, and a cammed surface on said operating member cooperating with a mating cammed surface on said pivoted member effective when said operating member is in its intermediate position for rotating said pivoted member against its bias to a second position wherein said depressor spring is disposed clear of said locking member in its said other position and in the said one extreme position of said operating member permitting rotation of said pivoted member to a position intermediate its said first and second positions, said

pivoted member in said intermediate position actuating said depressor spring into engagement with said locking member in its said other position.

15. In a lock device, an operating member slidably mounted for movement between an intermediate and two extreme positions, means for biasing said operating member to its said intermediate position, a pivotally supported locking member rotatable between two positions in one of which said locking member coacts with said operating member for preventing movement of said operating member from said intermediate position to one of said extreme positions, means for rotating said locking member about its pivots to the other of said two positions wherein said locking member permits movement of said operating member from said intermediate position to said one extreme position, a pivoted member provided with a depressor spring, means for biasing said pivoted member to a first position wherein said depressor spring rides on said locking member in its said one position, a cam for said operating member, a cooperating cam follower for said pivoted member, the surfaces of said cam and follower effective when said operating member occupies its intermediate position to rotate said pivoted member against its bias to a second position in which said depressor spring is lifted clear of both of said one and said other positions of said locking member, and said surfaces effective when said operating member occupies its said other position for positioning said pivoted member in an intermediate position in which said depressor spring rides on said locking member in its said other position.

16. In a lock device, an operating member slidably mounted for movement between an intermediate and two extreme positions, means for biasing said operating member to said intermediate position, a locking log rotatable between two positions in one of which said dog coacts with said operating member for preventing movement of that member from said intermediate position to one extreme position while freely permitting movement of said member from said intermediate position to the other of said two extreme positions, means for rotating said locking dog to the other of said two positions in which said dog frees said operating member for movement, a pivoted lever biased to a first position and carrying a cam follower, a cam on said operating member engaging said cam follower to rotate said pivoted lever to a second position in the intermediate and one extreme position of said operating member, a pivotally supported indication member biased to a first position, means operated by said pivoted lever in its said first position for operating said indication member to a second position, and means operable by said locking dog in said other position for operating said indication member to a third position.

17. In a lock device, an operating member mounted for movement between an intermediate and two extreme positions, means for biasing said operating member to said intermediate position, locking means coacting with said operating member for preventing movement of that member from said intermediate position to one extreme position while freely permitting movement of said member from said intermediate position to the other of said two extreme positions, means for controlling said locking means to free

said operating member for movement between said intermediate and said one extreme position, and indication means operatively connected with said operating member and said locking means for displaying a first or a second indication according as said member occupies its said other extreme position or its said intermediate position, and a third indication when said locking means is controlled to free said member for movement to its said one extreme position.

18. In combination, an operating member slidably mounted for movement between two positions, means for biasing said member to one of said two positions, manually operable means for moving said member against its bias to the other of said two positions, an operating element on said member moved into and out of an operating position according as said member occupies said one or said other position, a pivoted member biased to one position and operated against said bias to another position by said operating element in its said operating position, contacts operable between two positions, and a contact driving member operatively connecting said contacts with said pivoted member for operating said contacts to one or the other of said two positions according as said pivoted member occupies its said one or said other position.

19. In a lock device, an operating member slidably mounted for movement between two positions, means for biasing said member to one of said two positions, manually operable means for moving said member against its bias to the other of said two positions, a cam element on said member, a pivoted member, means for biasing said pivoted member to one position, a cam follower carried by said pivoted member and disposed for engagement by said cam element in said one position of said operating member for rotating said pivoted member against its bias to a second position, contact elements operable between two positions, a contact driving member provided with a pair of insulating sleeves for each contact element, said sleeves disposed on either side of the associated contact element, and a connection between said pivoted member and said contact driving member for driving said contact members between said two positions.

20. In combination with a stretch of railway track including a track switch provided with a switch throwing mechanism operatively connected with a throw rod, a lock device for said throw rod comprising a jaw for receiving said throw rod, a latch operable between two extreme positions in one of which said latch projects into said jaw for preventing movement of said throw rod past said latch and in the other of said positions said latch is withdrawn from said jaw, a slidably mounted operating member operatively connected with said latch, means for biasing said operating member and said latch to a position intermediate the said two extreme positions of said latch, fixed contact members, co-

operating movable contact members, a contact operating member operatively connected with said movable contact members for driving such members into and out of engagement with the cooperating fixed contact members, a cam for said slidably mounted operating member, a co-operating cam follower operatively connected with said contact operating member, the surfaces of said cam and follower formed so that in the 5 10 15 20 25

said one extreme position of said latch said movable contact fingers are positively driven by said contact operating member out of engagement with the cooperating fixed contact fingers and in the said intermediate and said other extreme position of said latch said movable contact fingers are positively driven by said contact operating member firmly into engagement with the co-operating fixed contact members, and circuit connections extending between one rail of said track and said fixed contact fingers and between the other rail of said track and said movable contact fingers, whereby a low resistance path between the track rails is established when said fixed contact fingers are engaged by said movable contact fingers.

21. In a lock device, a latch movable into and out of a jaw disposed to receive a throw lever, a housing enclosing an operating member operatively connected with said latch for controlling movement of said latch, locking means in said housing coacting with said operating member for preventing movement of that member to a position enabling movement of said latch out of the jaw, an electromagnet in said housing having an armature operatively connected with said locking means for operating said locking means out of engagement with said operating member when said armature is attracted by energization of said electromagnet, a key operated lock mechanism mounted in said housing accessible from the exterior, a spring member in said housing, and cooperating cams on said spring and lock mechanism for respectively driving said spring into and out of engagement with said armature according 30 35 40 45

as a key is or is not rotated in said lock mechanism, said spring in engagement with said armature driving said armature to its attracted position for operating said locking means out of engagement with said operating member.
